BRASSIERE

Henry M. Plehn, 730 Park Ave., New York, N.Y.

Filed Dec. 9, 1959, Ser. No. 858,542

4 Claims. (Cl. 128—489)

This invention relates to ladies' undergarments and more particularly to a bust molding garment, commonly known as a brassiere.

Brassieres have been universally adapted to support and mold the female bust and thus enhance the female figure. In spite of the multifarious sizes and shapes of the female bust, various structures have been designed which adequately serve to support and mold the average bust of the wearer of a brassiere. It has been the practice, however, in the undergarment industry, to give prime consideration to an average size and shape of a female bust in deference to the problem of mass production of the garment. It is, however, a known fact that such average sizes and shapes are quite arbitrary, leaving a great majority of wearers of brassieres ill fitted because of the establishment of such arbitrary size and shape constructions. It is further an established fact that even where a brassiere is adequately fitted within the average standards set by the industry, the female bust is subject to constant physiological change and is therefore impossible of being subject to mathematically precise measurements and fitting. It is thus obvious that a brassiere which may be considered perfectly fitted to a female figure at the moment of fitting, will be ill fitted as the normal physiological change of the busts results in changes in size and shape thereof.

It is therefore an object of the present invention to provide a brassiere which is responsive to the physiological changes in a female bust which alters its size and shape. At the same time, a brassiere, constructed in accordance with my invention, will take care of any slight variations in size or shape of the cups required to fit any wearer of a bust size even approximating, but not precisely the exact size and shape required for any particular bust.

Another object of this invention is to provide a brassiere which will continue to be of perfect fit and comfortable to a wearer in spite of such physiological change in the shape and/or size of a female bust.

A further object of the present invention is the provision of a brassiere which will offer adequate support to the female bust without undue compression of the busts in spite of constant physiological change thereof.

Still a further object of the present invention is to provide a brassiere which will furnish individual requirements of fit regardless of the individual variations of size and shape of the female bust, and which will give adequate support, confining effect, and proper shaping irrespective of size, shape, or other characteristic of the bust.

In accomplishing the foregoing, there is provided a brassiere having a novel bust cup construction which, although furnishing adequate restrictive control and support to the breasts, provides a garment which is nevertheless sufficiently yieldable to be comfortable in ordinary usage, will provide a suitable size of bust cup for the "in-between-size" wearer, and is also responsive to the physiological changes in size and shape of the female

2

bust. The cups of the brassiere of the present invention are constructed of a fabric with controlled expandability. By the provision of a two directional highly stretchable fabric incorporated with a substantially non-stretchable material, the resulting substantially one-way stretchable fabric of limited yieldability is utilized in the bust cups to yield a radial stretch, so that the bust cups of the present invention will furnish positive support to the female bust while being entirely responsive to even the slightest physiological change in the size and shape of the female bust.

The above and further objects and advantages of the present invention will be apparent to those versed in the art, from the following description of a specific embodiment of the invention as illustrated in the drawing, wherein like characters designate like parts in the several views, and in which:

Fig. 1 is a front view of a brassiere constructed in accordance with the present invention;

Fig. 2 is a cross-sectional view taken on line 2—2 of Fig. 1; and

Fig. 3 is a view of the fabric utilized in the construction of the bust cups of the brassiere according to the present invention and shown in an extended position.

Referring now to the drawing, there is shown a brassiere 10 having bust cups 11 and 12, each having a top edge 13 forming the top edge of the garment to which are attached shoulder straps 26, 27, and lower arcuate edges 14 and 15. Contiguous to the lower edges 14 and 15 and disposed beneath the respective bust cups 11 and 12 and secured thereto is a horizontal stretchable fabric 16 and 17. Central non-stretchable portion 18 is disposed between and separate bust cups 11 and 12. Such central non-stretchable portion 18 has edges 19 and 20 secured partly to bust cups 11 and 12 and secured partly to stretchable fabric 16 and 17. Incorporated in the lower part of non-stretchable portion there is provided a padded portion 21 to give additional comfort to the wearer.

Adjacent the outer side edge of each bust cup 11 and 12 are body encircling bands 22 and 23 which consist of non-stretchable fabric. Such body encircling bands 22 and 23, respectively, have edges 24 and 25 secured partly to bust cups 11 and 12, and in part secured to the horizontally stretchable portions 16 and 17, respectively.

Bust cups 11 and 12, as shown in the illustrated embodiment, are constructed of a fabric 30 comprising alternate strips of a highly extensible two-way stretch mesh material 31 of a net-like construction, incorporated by stitching 32 with strips of a non-stretchable material 33, the resulting fabric 30 having a one-way stretch characteristic.

Although a non-stretchable material 33 is shown, such material 33 may be one which is of lesser stretchability than the highly stretchable net material 31. The use of a material 33 of lesser stretchability than the net material 31 will thus yield a fabric 30 having a stretch characteristic which is greater in one direction than another.

The non-stretchable material 33 may be of a single 60 ply seamed by stitching to extensible net material 31, or may consist of a double ply 33, 33' as illustrated in Fig. 2, in which case the longitudinal edges of material 31 are interposed within the longitudinal edges of the double 65 ply of material 33, 33' and joined thereto by stitching 32.

The width of each of the strips of net material 31 and non-stretchable material 33 may be altered or may be similar depending upon the requirements of yieldability of the final garment. Thus, for example, broader 70 strips of non-stretchable fabric may be used.

Since both bust cups are substantially identical, refer-

ence will be made to one such cup using bust cup 11 as illustrative thereof. Bust cup 11 is provided with four sections or quadrants 35, 36, 37, 38 each of such sections being substantially triangular in form, the radius of each quadrant being parallel with the direction of the stretch of the fabric 30. Such sections are joined by fagoting 39 so that stretchability of the cups is not unduly impeded. The resulting stretchability of the cup is thus radial from the center of the cup outwardly.

Although the strips 31 and 33 of the fabric 30 are illustrated as being in a parallel plane to the direction of yieldability in each of the triangular quadrants of the bust cup 11, it is also intended that such strips 31, 33 may assume an arcuate shape. The bust cups 11 may also be constructed in two sections rather than being constructed of quadrant sections. The bust cups of the present invention may further be made to conform to the shape of the bust by the utilization of a unitary blank of fabric 30 thereby eliminating the need of sections in the construction of said cups 11 and 12.

It is evident that the foregoing construction of the present invention is entirely responsive to radial stress of the normal female bust and is yieldably responsive to enlargement or other physiological change or other size adjustment of the bust so that adjustment to a particular size and shape will be automatic.

It is to be understood that although the present invention has been described and shown in the drawing, with reference to one embodiment, it is to be noted that various embodiments and adaptations may be made without constituting a departure from the spirit and scope of the invention as herein described and defined. For instance, while a four-section cup brassiere has been illustrated and described, the invention is equally applicable to a brassiere constituted of conventional bust sections shaped to breast conformation, as heretofore described.

I claim:

1. A brassiere having a body encircling portion and bust cups attached thereto; means separating said bust

10 15 20 25 30 35

5 cups; each of said bust cups comprising a fabric having a plurality of strips of elastic material and a plurality of strips of substantially non-elastic material, said strips of elastic material being alternately disposed with respect to said strips of substantially non-elastic material along the longitudinal edges thereof and joined along said edges.

2. A brassiere having a body encircling portion and bust cups attached thereto; means separating said bust cups; each of said bust cups comprising at least four alternating strips of stretchable fabric and non-stretchable fabric attached along the longitudinal edges thereof to each other.

3. A brassiere having a body encircling portion and bust cups attached thereto, means separating said bust cups, each of said bust cups comprising a fabric having two layers of semi-elastic strips of material, the longitudinal edges thereof being turned inwardly, and two-way elastic strips interposed between said turned in edges of said semi-elastic strips wherein said semi-elastic strips and said two way elastic strips are integrally incorporated to form a substantially one way elastic material.

4. A brassiere having a body encircling portion and bust cups attached thereto, means separating said bust cups, each of said bust cups comprising a fabric having a plurality of semi-elastic strips of material, the longitudinal edges thereof being turned inwardly, and elastic strips interposed between the turned in edges of said semi-elastic strips, said semi-elastic strips and said elastic strips being of varied widths, wherein said elastic strips and aid semi-elastic strips are integrally incorporated to form a substantially one-way elastic material.
